FORM FOR CASTING CONCRETE WALLS

Warren Hyre, Chattanooga, Tenn.

Application October 17, 1947, Serial No. 780,409

8 Claims. (Cl. 25—131)

1

This invention relates to forms for casting concrete and especially walls whether solid or hollow or provided with cavities which may carry pipes or cables or the like. The two walls and the hollow space therebetween may be formed to any desired thickness. The forms may comprise units or panels or face plates or sheets of any suitable material, size or shape. Preferably, the panels will have substantially straight sides so that they can be placed side by side and in contact with each other so that they may be assembled into suitably sized areas to form sides of walls to be cast. At least one side of each panel may be cut away or offset at both top and bottom. Extending back at a right angle from the face plates of the panels may be a reinforcing frame of angle members or walls which may be integral with the face plate or may be fastened thereto by any suitable means. The position of the peripheral walls or angles may follow the contour of the periphery of the face plate including the cutaway or offset portions. The peripheral walls or angles may be perforated at suitable intervals, which preferably will be uniform, so that the perforations may engage pins or the like for suitably positioning the units or panels or for properly joining them together.

Positioning members or aligner clamps may be provided for arranging on the footing or other base on which a wall is to be cast. These positioning members may be fixed in place by having their ends turned over the sides of the base or they may be spiked thereto or to stakes driven in the ground adjacent the base. The positioning members or aligner clamps may engage the panel members by suitable means including pegs or pins which may engage in the holes in the peripheral walls or angles of units or panels to hold their bottom edges properly in place. Connecting or tie rods or bars may be provided for holding the panel units in proper position and at proper distance from each other to produce the wall desired. These tie rods may rest in the offset portion of the units and may have perforations registering with perforations in adjacent peripheral angles or walls so that a single pin may engage the connecting bar and the units on each side of it. The tie rods may be tapered so as to be more readily removable after the concrete is cast or they may be weakened at suitable points so that the projecting parts may be broken off back of the face of the concrete, leaving parts of the bars in the concrete but the surface free.

The pin for engaging the units and the connecting bars may be carried on a bar or member which may also carry an open socket which may

2

be tapered at the opening to engage the contacting peripheral angles or walls of adjacent units so as to hold them in contact and so produce a substantially unbroken surface for the form.

5 When a solid wall is to be cast, panels or units may be placed on each side of it, but when a hollow wall is to be cast it may be desirable that between the panels to form the outer surfaces of the wall there be placed an inner series of panels to form or outline the hollow and these may be closed or shut off at their ends to prevent concrete entering the space between them.

A member forming a temporary top tie may be provided to be arranged at the top of the forms, 15 having a plate mounted thereon, carrying downwardly projecting pins to hold and position the two inner rows of panels or units forming the hollow, and the body of the tie spanning the hollow and designed to hold and position the outer panels or units, and to produce a socket or seat 20 in the top of both parallel walls when cast, so that when the member is removed it may be replaced by a corresponding member, or permanent top tie having a plate mounted thereupon, carrying upwardly projecting pins or other means to receive and properly position the bottom of the 25 two inner rows of panels or units constituting a hollow form for an upward extension or portion of the wall to be cast.

A removable tie or a tie designed to break-off 30 back of the outer wall's surface may be used adjacent to the top of the permanent tie to hold and position the bottom of the two outer rows of panels or units constituting a form for an upward extension or portion of the wall to be cast.

35 Special form members may be provided for the outward angle and for the inward angle of turns or corners in the wall whether it be solid or hollow at the turn.

40 These and other purposes and details of the invention will appear from the following description and the accompanying drawings illustrating specific embodiments of the invention which is not confined to the specific details of the showing made.

45 In the drawings, Figure 1 is a fragmentary view of panels assembled with a tie-rod and all held together with a clamp. Fig. 2 is a perspective view of a clamp. Fig. 3 is a side elevation of one end of one type of connecting bar or tie-rod. Fig. 4 is a side elevation of the device of Fig. 3. Fig. 5 is a side elevation of a tapering tie rod. Fig. 6 is a side elevation of a wedge for loosening the bar of Fig. 5. Fig. 7 is a fragmentary vertical section on the line 7—7 of Fig. 1. Fig. 8 is a plan view

of an assembly of panels to form a wall partially solid and partially hollow. Fig. 9 is a side elevation of an optional form of removable tie rod. Fig. 10 is a side elevation of a form of tie rod to replace the tie rod of Fig. 9. Fig. 11 is a plan view of a cast hollow wall with the tie rod of Fig. 10 in place therein. Fig. 12 is a plan view of one form of aligner which may be employed to position form units. Fig. 13 is a vertical section on the line 13—13 of Fig. 12. Fig. 14 is a side elevation of another form of aligner. Fig. 15 is a fragmentary plan view of the aligner of Fig. 14. Fig. 16 is a fragmentary sectional view showing the tie rod of Fig. 9 in place. Fig. 17 is a fragmentary sectional view showing the spacer tie of Fig. 11 in place and positioning frames for upper parts of walls.

Forms for concrete may be made of assembled panels 20 made up of face plates 21 which may be of square or rectangular or any other suitable form. They are shown as square. The panel face plates are preferably cut out at least one edge at top and bottom as shown at 22 for a purpose to be explained. Preferably, the face plates are backed and reinforced by angle bars 23 which may extend about their entire peripheries and also at suitable intermediate points, if desired. The peripheral angle bars are bent and formed as at 24 to hollow the contour of the cut out portions 22. Perforations 25 are provided in the upstanding wings of the peripheral angle irons. A perforation is in the bent portion 24 and they are distributed preferably at regular intervals throughout so that when adjacent panels are brought into side by side contact the perforations may register and be used for positioning and fastening together panels. As shown in Fig. 1, a smooth or uncut edge of one panel may be brought into contact with a cut edge of an adjacent panel so that the portions 24 may form seats or sockets for connecting rods 26 in the ends of which are perforations 27 so positioned that when they are brought into register with the perforations in the panels they may position the panels the proper distance apart to form a wall of the desired thickness when concrete is poured into the form. In Fig. 1 the tops of adjacent panels are shown as level but obviously they need not be. A top hole in the side of one panel may be put in register with a lower hole on an adjacent panel. The panels and connecting rods may be held in proper relative position by any suitable means, such as pins, passing through the holes. Such a pin 28 is shown as mounted on a rod or bar 29 acting as a handle and carrying a clamp 30 which may enclose and hold together peripheral angle bars 23 of adjacent panels 20. The outer edge of the clamp 30 may be slightly tapered or turned out, as at 31, as indicated in Fig. 2, so as to facilitate installation on the angle bars 23.

Various forms of tie rods may be used. As shown in Fig. 3, portions may be cut out on one or both sides as at 32 to weaken the rod so that after the panels are removed from the cast wall, the tie rods may be broken off within the wall so as to leave cleared surfaces. As indicated in Figs. 3 and 4, the portions 33 cut out at 32 may be retained and turned in the same or opposite directions so as to engage and seat firmly in the poured concrete. This may facilitate the breaking off of the protruding ends by forming a sturdy seat for the body of the tie to resist the breaking action when the protruding ends are struck the breaking blow. A blow of a ham-

mer on the protruding ends of the tie bars may break them off. When desired, a tapering tie rod 34 may be employed, having a slot 35 at its larger protruding end. About the slotted end 5 may be placed a washer 36 resting against the angle bars 23 of the panels (see Fig. 8). After the concrete is cast, a wedge 37 may be driven into the slot 35 and exert pressure against the washer or buffer 36 and loosen the rod 34 so that it may be withdrawn and used again if desired.

In order to position properly the panels of the forms on the base or footing 41 for the wall, there may be provided an aligner 38 provided with holes 39 on one or both ends through which 10 may be driven a spike 40 into the base 41 to hold it in the desired position. The aligner may be provided with upwardly extending pins 42 to engage perforations 25 in the bottoms of panels 20 to hold them in proper position for the desired 15 wall thickness. The pins 42 shown in Figs. 14 and 15 may be placed the proper distance apart to engage end holes 25 in the bottoms of adjacent 20 panels 20 so as to bring the edges of their faces and angle bars 23 into close contact to receive 25 the clamp 39 and present an unbroken face to the concrete to be poured. Instead of using pins on the aligner there may be provided a strip 43 with struck up portions 44 suitably spaced to engage and grasp the sides of the angle bars 23 so 30 as to hold the panels in proper desired position. When the ends of adjacent panels are inserted 35 between the same pair of portions 44 (e. g. the two at the left of Fig. 13), the panels will be positioned to present a smooth surface to the poured concrete. If it is not desired to employ 40 perforations to position the aligner, there may be used to seat 45 provided with a perforation 46 for a dowel or spike to fix it to the base. Clips 47 struck up from 45 may be provided and after 45 the strip is adjusted transversely to 45 to the proper position, the clips 47 may be hammered down to clasp and rigidly hold the strip. The aligners are shown adapted to position four rows of panels, but they may have some of the pins 42 or struck up portions 44 omitted or be used for only two rows of panels.

For a solid wall two rows of panels, as indicated in Fig. 1, may be sufficient. An arrangement for a hollow wall or a partially hollow wall is indicated in Fig. 8. Outer rows 48, 49 of panels 50 may be associated with inner rows 50, 51. The face plates 21 of row 50 may face those of row 48 and those of row 49 face those of row 51, thus leaving space between the backs of the rows 50 and 51 free of concrete and leaving hollows in the wall for pipes, cables, etc. At the ends of the rows 50 and 51 may be provided solid blocking strips 52 to prevent concrete from entering between the rows 50 and 51. The strips 52 may have edges perforated to cooperate with the perforations of the peripheral angle bars of the panels of rows 50 and 51 for holding them in position, or may have a plate attached at right angle to top with perforations registering with two of pins 57 in tie 54. Where the wall turns 60 there may be provided angle panels 20a formed at the desired angle of the wall turn. At the outer side of the wall turn these special panels 20a may not be needed but angle bars 53 may be used having both wings perforated to register and cooperate with the adjacent panels for positioning and holding in position.

In this hollow wall arrangement the aligner strips may be employed provided as shown in Figs. 12 to 15 with mechanism for receiving the

four courses of panels and are used only with the base or bottom rows of panels. Special tie bars such as shown in Figs. 9, 10 and 11 (see also Fig. 8) may properly space and hold together the panels of rows 48, 49, 50 and 51. A bar 54 resting in the cut out portions or bends 24 in the angle bars of all four rows 48, 49, 50 and 51 may be provided with holes 55 registering with and cooperating with the holes in the peripheral bars 23 of the outer rows of panels 48 and 49. At its center, the bar 54 may be provided with an overlying plate 56 carrying depending pins or with perforations for inserting pins 57 to engage the holes in the panels of the inner rows 50 and 51. Lugs or arms 58 extend laterally from the bar 54. After the concrete is cast, the bar 54 may be knocked upwardly. It will leave in the concrete a recess, being an impression of it and its lugs 58. The inner rows of panels or units 50 and 51 are then removed. A correspondingly formed but shorter tie bar 59 has at its ends lugs or arms 60 positioned to enter the recesses formed by the arms 58. The bar 59 also carries a plate 61 but provided with upwardly extending pins 62 so as to engage panels 50a and 51a and hold them directly above the position occupied by the panels of the inner rows 50 and 51 previously removed. Thus, when the wall is carried to a greater height, as shown in Fig. 17, the bars 59 will insure the sides of the hollow in the wall being straight and smooth up and down. The bars 59 will be covered with concrete and may be left in the walls and, since their area is relatively small, they may not unduly block or impede the hollow space in the finished wall, while at the same time permanently tying the two walls together as a single unit.

In Fig. 2 is shown a hole 70 in the rod or bar 29. When the clamp 30 is in the position shown in Fig. 1 the hole 29 will be in register with holes 25 so that a nail or the like may be passed through the holes to lock or hold the clamp in place.

The specific sizes, shapes and details of the structures illustrated may be varied within wide limits since they form no part of the invention which may be embodied in other structures.

I claim as my invention:

1. In a form for casting concrete walls to be erected on a base, a plurality of panels arranged in two rows for the outer surface of the walls, the panels of the rows being disposed in register and each comprising a face plate having cut-out portions at top and bottom of one side edge thereof, and perforated angle bars on the outer side of each face plate and along its periphery, aligners on the base onto which the wall is to be cast, upwardly extending pins in the aligners engaging perforations in the angle bars at the bottoms of adjacent panels to hold them in contact and in proper position for desired wall widths, perforated tie rods extending through the registering cut-out portions of the panels, pins extending through registering perforations in tie rods and angle bars, handles for the pins, clamps on the handles enclosing and holding together the angle bars of contiguous panels in each row, angle bars at the outer corners of the panel rows having perforations registering with the perforations of the angle bars of contiguous panels, pins through the perforations of the corner angle bars and the panel angle bars, and clamps engaging the corner angles and the panel angles and holding the corners rigid.

2. In a form for a concrete wall to be cast on

a base, inner and outer rows of panels, peripheral walls on the panels having spaced perforations, an aligner device extending transversely between the rows of panels and being perforated for fixing in a predetermined position on the footing or base for the wall, and spaced pairs of upwardly extending projections on the aligner device engaging in appropriate perforations in the bottom peripheral walls of the panels of both rows, thereby to secure the panels of the rows in properly spaced relation and against spreading forces, the projections of the pairs being spaced from one another and engaging in appropriate perforations in the bottom peripheral walls of adjacent panels to lock the adjacent panels of the rows together.

3. In a form for a concrete wall to be cast on a base, rows of adjacent panels, peripheral walls on the panels having spaced perforations, an aligner device extending between the rows and perforated for fixing in a predetermined position on the footing or base for the wall, and spaced pairs of upwardly extending pins on the aligner device engaging in appropriate perforations in the bottom peripheral walls of the panels of both rows, thereby to secure the panels of the rows in properly spaced relationship and against spreading forces, the pins of the pairs being spaced from one another and engaging in appropriate perforations in the bottom peripheral walls of adjacent panels to lock the adjacent panels of the rows together.

4. In a concrete hollow wall form comprising outer and intermediate series of panels each composed of a plurality of contiguous panels having aligned seats at their tops in all series for tie rods, a removable tie rod in the seats at the tops of the panels, lugs perpendicular to the rod in the spaces between the outer panels and the intermediate panels, to form seats in the top of the cast concrete, and a permanent tie rod engaging the seats, and pins on the permanent tie rod extending upwardly engaging and positioning contiguous panels of forms for walls to be cast thereabove.

5. In a form for casting concrete walls to be erected on a base, a plurality of panels arranged in two rows for the outer surface of the walls, the panels of the rows being disposed in facing relation and each comprising a face plate having a cut-out in a top corner portion thereof and perforated angle bars on the outer side of each face plate extending along its periphery, means cooperating with the perforated angle bars for securing the bottoms of the facing panels of the rows in properly spaced relation and for securing the bottoms of adjacent panels of each row in proper alignment, and rectangular tie bars arranged on edge and extending between the tops of the facing panels, said tie bars each having a body portion which is adapted to be embedded in the concrete wall being cast, and perforated end portions seating in the cut-outs in the top corner portions of the panels, securing pins extending through registering perforations in the end portions of the tie bars and the side angle bars of adjacent panels for similarly securing the tops of the panels properly spaced and aligned, said tie bars each having weakened vertical sections in its body portion which are disposed inwardly from the inner faces of the panels, whereby upon removal of the panels from the cast wall the end portions of the bars may be broken away from the embedded body portions thereof inwardly of the surfaces of the cast wall.

6. In a form for casting concrete walls to be erected on a base, a plurality of panels arranged in two rows for the outer surface of the walls, the panels of the rows being disposed in facing relation and each comprising a face plate having a cut-out in a top corner portion thereof and perforated angle bars on the outer side of each face plate extending along its periphery, means cooperating with the perforated angle bars for securing the bottoms of the facing panels of the rows in properly spaced relation and for securing the bottoms of adjacent panels of each row in proper alignment, and rectangular tie bars arranged on edge and extending between the tops of the facing panels, said tie bars each having a body portion which is adapted to be embedded in the concrete wall being cast, and perforated end portions seating in the cut-outs in the top corner portions of the panels, securing pins extending through registering perforations in the end portions of the tie bars and the side angle bars of adjacent panels for similarly securing the tops of the panels properly spaced and aligned, the body portion of each side bar inwardly of its end portions having vertically disposed aligned cuts extending towards one another from the upper and under edges of the bar, and integral triangular wings extending at an angle to the bar and being disposed inwardly of said vertical cuts, said wings being formed by 30 triangular areas of the bar defined by said vertical cuts and the upper and under edges of said bar, respectively, said cuts providing weakened vertical sections in the bar disposed inwardly from the inner faces of the panels whereby, upon removal of the panels, the end portions of the bars may be broken away from the embedded body portions thereof inwardly of the surfaces of the cast wall.

7. A tie bar for concrete wall forms comprising a substantially flat bar adapted to extend on edge between inner and outer wall forms and

having a body portion and co-planar end portions adapted to be cooperated with adjacent form members, the body portion of said bar inwardly of said end portions having vertically disposed, aligned cuts extending towards one another from the upper and under edges of the bar, and integral triangular wing portions extending at an angle to the body portion and being disposed inwardly from the vertical cuts, so as to increase the rigidity of said body portion, said wings being formed by triangular areas of the bar defined on two sides by the vertical cuts and the upper and under edges of the bar, respectively, the construction and arrangement being 15 such that upon removal of the form members said end portions can be broken away from the body portion by a vertical blow applied either to the upper or under edges of said end portions.

8. A tie bar for concrete wall forms as set forth in claim 7, wherein the triangular wings are disposed approximately at right angles to the body of the bar and extend from opposite sides thereof.
